UNITED STATES PATENT OFFICE.

CHARLES ADAMS-RANDALL, OF BOSTON, MASSACHUSETTS.

LOUD-SPEAKING TELEPHONE-RECEIVER.

1,083,788.

Specification of Letters Patent. Patented Jan. 6, 1914.

Application filed May 16, 1913. Serial No. 768,053.

To all whom it may concern:

Be it known that I, CHARLES ADAMS-RANDALL, a citizen of the United States, residing at Boston, in the county of Suffolk and 5 State of Massachusetts, have invented certain new and useful Improvements in Loud-Speaking Telephone-receivers; and I do hereby declare the following to be a full, clear, and exact description of the invention, such as will enable others skilled in the art to which it appertains to make and use the same.

This invention relates to telephone receivers, and has for its object to provide a 15 loud speaking electric telephone receiver which will be more efficient in action and therefore more satisfactory in use than those heretofore proposed. That is to say, heretofore a large class of receivers have been 20 constructed with an electromagnet associated with a permanent magnet, as well as sometimes without the permanent magnet. But the magnetic means employed have been usually inclosed in a suitable case, upon the 25 outer, open end of which a magnetic armature or diaphragm has been arranged in close proximity to the pole-ends of the magnet and firmly clamped to the case by means of a suitable ear-piece, without employing 30 a resonator. In such arrangements, the diaphragm is vibrated by the variations of the magnetic field in which it is held. Such vibrations, of course, cause a vibration of the air between the diaphragm and the ear, 35 and the volume of sound is generally found sufficient for commercial purposes provided the receiver is held sufficiently close to the ear. But such volume is not as great as is desired under all conditions, and many 40 devices have been tried for augmenting the volume of the tones thus produced, to the end that the reproduced sounds may be heard at greater distances. Chief among these 45 devices are the well known horns or megaphones of various forms and material. There are serious objections, however, to the megaphone as generally made and used, for although the volume of tone is in some instances increased, its clearness and natural- 50 ness is generally impaired; and especially is this the case in the reproduction of articu- late speech, for here the minor vibrations are lost and the articulate words distorted thereby giving a "fog-horn" effect, so that 55 the reproduction is neither clear, natural, nor distinct.

To overcome these serious and well known defects, while providing a commercially practical instrument is among the objects of this invention. 60

To this end, the invention involves more particularly a construction comprising the well known magnet of the telephone receiver, and a suitable resonator, in which the diaphragm, armature, or vibrator forms 65 a part of or coacts with the said resonator. The resonator thus takes the place of a megaphone and serves to reproduce the words or sounds transmitted, more naturally and clearly and with a greater volume than 70 has been possible heretofore.

The diaphragm forming a part of the resonator, may be a magnetic plate of any desired form, or it may be composed of a series of magnetized wires of the same or 75 of different diameters or lengths, or it may consist of both classes of wires, so they will have different rates of vibration. With such a construction, the changes of the density of the magnetic field, and of the magnetic 80 waves are more faithfully set up in the dia- phragm, and the resulting air waves of speech and other sounds are reproduced with their natural characteristics.

The operation of this invention may be 85 likened to that of a violin, in which the resonator or body of the violin is set in vibration by the manual vibration of its strings, the resonator or the body of the violin, augmenting greatly the volume of tone, while at 90 the same time preserving all of the characteristics of each string and the notes produced by the fingering.

In this invention the vibrations of the resonator are produced electro-magnetically 95 through the diaphragm, and on the prin- ciples above stated, the volume of sound is increased, while the characteristics of the vibrations are preserved.

Referring to the accompanying drawings 100 forming a part of this specification, in which like numerals designate like parts in all the views—Figure 1 is a diagrammatic plan view partly broken away of a receiver made in accordance with my invention; Fig. 105 2 is a side elevational view of the parts shown in Fig. 1; Fig. 3 is a detail plan view of a modified form of diaphragm member; and Fig. 4 is a cross sectional view of the parts shown in Fig. 3. 110

1 indicates my resonator which may be of any desired form and of the usual material,

the particular forms illustrated being found suitable. In the form shown in Figs. 1 and 2, I attach to the resonator body 1 the bent supports 2, 2, of wood, aluminum or other suitable material, and I preferably place wooden blocks or washers 3 between said supports and resonator as shown. Screw members 4 passing through said washers and supports serve to adjustably hold the latter to the resonator body. The said supports are provided with the slots 5 to facilitate their adjustment relative to the screws 4, as shown. Any suitable guiding means 5' may, if desired, be employed to govern the up and down movement of the said supports 2. Also attached to the resonator are one or more sounding posts 6 similar to like members employed in violins and similar instruments.

20 On the top of the resonator 1, I suitably secure a magneto telephone receiver 7, preferably of the type called "watch case" and in which there is assembled a plurality of permanent magnets 8 having the pole pieces 9.

25 On these pole pieces there is further attached the electromagnet 10 having the poles 11. Suitably attached to the supports 2, is the plate diaphragm 12, which is so positioned as to lie just above and in close proximity to said pole pieces 11. I prefer to employ diaphragms of different lengths, or diameters, when circular diaphragms are used, and to this end I provide clamping plates 13 adapted to be adjusted and held to 30 the supports 2 by means of the screws 14, entering the different sets of holes 15, 16 and 17. By this means diaphragm plates 12 of any desired area may be used. It will now be clear that the electromagnetic 35 vibrating means comprising the magnet 10 is permanently attached to the sounding box, as well as the diaphragm 12, so that any vibrations that may be imparted to the latter will be reinforced by the said box or 40 resonator 1.

In the modified form of construction shown in Figs. 3 and 4 the diaphragm is composed of a plurality of magnetized wires 18 of different sizes as shown. In this case each 45 wire will have a tendency to vibrate in unison with an air wave of its own period, and therefore the whole diaphragm is adapted

to pick up reproduced waves of different periods and to reinforce them by means of the sound box. A cushion 19 which may be 55 of leather or other material is preferably interposed between the members 13 and 18 as shown.

It is obvious that those skilled in the art may vary the details of construction as well 60 as the arrangement of parts without departing from the spirit of my invention and therefore I do not wish to be limited to the above disclosure except as may be required by the claims. 65

What I claim is:—

1. In a loud speaking telephone receiver, the combination of a resonator; a diaphragm comprising a plurality of wires having different periods of vibration and of magnetic 70 material rigid with said resonator; magnetic means rigidly associated with said resonator and diaphragm; and means for adjusting the relation between said magnetic means and said diaphragm, substantially as described. 75

2. In a loud speaking telephone receiver, the combination of a box-like resonator; a pair of supports adjustably secured to said resonator; a diaphragm carried by said supports; means associated with said supports for adjusting and clamping said diaphragm thereon; and an electromagnet rigidly attached to said resonator in operative relation with said diaphragm, substantially as 80 described. 85

3. In a loud speaking telephone receiver, the combination of a box-like resonator; a pair of supports adjustably secured to said resonator; a diaphragm composed of a plurality of magnetic wires of different diameters carried by said supports; means associated with said supports for adjusting and clamping said diaphragm thereon; and an electromagnet rigidly attached to said resonator in operative relation with said diaphragm, substantially as 90 described. 95

In testimony whereof I affix my signature in presence of two witnesses.

CHARLES ADAMS-RANDALL.
